UNITED STATES PATENT OFFICE.

PAUL DE CHIME, OF YOUNGSTOWN, OHIO.

SUPPORTING-PEDESTAL FOR CASH-REGISTERS.

1,222,739.

Specification of Letters Patent. Patented Apr. 17, 1917.

Application filed October 15, 1915. Serial No. 56,162.

To all whom it may concern:

Be it known that I, PAUL DE CHIME, a subject of the King of Italy, residing at Youngstown, in the county of Mahoning and 5 State of Ohio, have invented certain new and useful Improvements in Supporting-Pedestals, of which the following are the specifications.

My invention relates to supporting pedestals for safe desk, cash register and other articles of office equipment, and has for its 10 primary object the providing of a pedestal so constructed that the base end can be fastened to the floor from the inside of the pedestal in such a manner that the object so mounted upon the pedestal cannot be removed from its place without first having a forked tool, with opposite points to engage the holes (h), to be used for turning this 15 nut, in order to obtain access to the fastening or anchoring means, or threaded end of the rod. With these and other objects in view, which will readily appear as the nature of the device is understood, the same 20 25 consists of a novel construction and combination of parts hereinafter illustrated, described and claimed.

In drawings, Figure 1 is a front elevation, showing a safe mounted upon the pedestal. Fig. 2 is a vertical section view 30 through the center of the pedestal; and Fig. 3 is a detail view showing the various parts in disassembled relation.

Similar reference characters designate 35 different parts of the device throughout the various figures of the drawings. R represents an anchoring rod provided at its lower end with the screw-threaded terminal or point (P) designed to be screwed into the 40 floor, as shown in Fig. 3 of the drawings, and also provided with the foot-piece or brace (f) through which the screw (E) is turned in the floor, as shown in Fig. 2, to prevent the rod from being turned. The 45 upper end of the rod (R) is provided with a threaded section to receive the inner threaded sleeve nut (N) with the enlarged head or flange portion, provided with holes (H). Fig. 2, is a sectional view of the tubular 50 standard (P) placed over the rod (R) provided with base (B) surrounding the foot-piece (f), representing a pedestal upon which is mounted a safe (S). This pedestal is

carried by the base (B), and is provided near its upper end with a shoulder (s), thus 55 forming the reduced portion or neck (n) upon which the collar (C) is placed, resting upon the shoulder (s). The bottom of the safe is provided with a central opening equal in diameter to that of the neck or 60 reduced portion (n) at the upper end of the pedestal (P). The inner face of the bottom of the safe may be recessed around the opening to provide a seat for the head of the nut (N), which comes even with the 65 inner face of the safe (S).

To assemble the parts, the rod is first screwed into the floor until the foot-piece (f) comes firmly in contact with the floor. The pedestal (P) is placed over the rod 70 (R), the base surrounding the foot-piece (f), and the collar (C) is placed in position on the shoulder (s). Then the safe is placed upon the pedestal, the neck (n) passing through the opening in the bottom of the 75 safe, and the sleeve nut (N) turned on to the threaded end of the rod (R), the sleeve portion of which extends in to the upper end of the tubular neck, for the purpose of securing the object to be supported to the 80 pedestal in such a manner that it can be revolved on the collar or reduced portion at upper end of the pedestal and it will not wobble or shake the fastening of the standard. It is also apparent that my construction affords secure means for sustaining 85 the pedestal in the desired position, and can be readily detached from the floor.

Having thus fully described my invention, what I claim as new, and desire to secure by 90 Letters Patent is—

In a supporting pedestal the combination of a tubular standard and central anchoring rod, said rod being provided at its upper end with a threaded section to receive an 95 inner threaded sleeve nut, the sleeve portion of which extends into the upper end of the standard, for the purpose of securing the object to be supported to the standard, and rod jointly, and means for securing said rod 100 to the floor.

PAUL DE CHIME.
